SLIDE PERCUSSION TOOL

George J. Moeller, Altadena, Calif., assignor to
Anthony Oberholtz, Los Angeles, Calif.

Application March 29, 1947, Serial No. 738,121

5 Claims. (Cl. 81—52.35)

1

This invention relates to a slide percussion tool and deals more specifically with a tool for performing pulling, driving or rotating operations, as desired.

Prior tools of the character indicated are conventionally provided with an external stop, usually in the form of an enlargement on the shank of the tool. This stop is hazardous in that the hand of the operator is frequently pinched between it and the slide handle or hammer grasped by said hand.

Accordingly, this invention has for an object to provide a percussion tool, as indicated in which the stops or movement limiting abutments are completely enclosed within the operating handle and the tool, thereby, rendered safe in operation.

Another object of the invention is to provide a slide percussion tool which is equally effective for driving operations, for pulling operations and for rotating operations, the tool being so designed that said operations may be selectively accomplished without change in the tool assembly.

My invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is an upper end view of the slide percussion tool contemplated in the present invention.

Fig. 2 is a longitudinal sectional view thereof, partly in elevation.

Fig. 3 is a cross-sectional view as taken on the line 3—3 of Fig. 2.

Fig. 4 is a bottom end view.

The tool which is illustrated comprises three essential elements, namely; a stem or shank 5, a handle or hammer 6, and a stop collar 7 fitted to the hammer 6 and maintaining the tool in assembly.

The stem 5 comprises a suitable turning or forging which is integrally formed with a lower extension 8, an intermediate boss or enlargement 9, and an upper extension 10. The extensions

8 and 10 are preferably co-axial and, although shown cylindrical, may be of any desired shape. The boss is formed as an annular flange larger than the extension and said flange, at one side, is removed to provide a flat 11. The lower end of the extension 8 is provided with a screw seat 12 or the equivalent thereof, for a suitable interchangeable element 13 according to the operation desired to be accomplished. Such an element may be formed as a driver or pusher, a puller, such as a valve puller, or a turner, or rotator, such as a spanner, screw driver, etc.

The handle or hammer 6 comprises a sleeve-like member having a hand-grasping cylindrical part 14 which is preferably knurled as at 15 and formed, at its upper end, with an annular flange 16. At said upper end, the hammer is provided with an axial internal thread 17 for the collar 7. Therebelow, a passage 18 is formed in the hammer, said passage extending from the threads 17 to a shoulder 19 at the opposite end of the hammer. The cross-sectional shape of passage 18 is similar to the shape of flange 9, being circular to accommodate said flange and having a flat side 20 to guide the flat 11. It is evident, by this arrangement, that the stem and hammer are in non-rotational association, the extension 10 and flange 9 residing within the passage 18. The passage 18 is extended beyond the shoulder 19 as a circular opening 21 through which the stem extension 8 extends.

The collar 7 is externally threaded for engagement with the internal threads 17 and said collar has an axial passage 22 of generally the diameter of the opening 21 for free movement therethrough of the upper stem extension 10. The thickened part 23 of the hammer serves as a shoulder 24 for the collar, as best seen in Fig. 2. The spanner slots 25 provide means whereby said collar may be tightened against shoulder 24 or removed. The bottom edge 26 of the collar is opposite to the shoulder 19 and both the shoulder 19 and said edge 26 serve as movement-limiting abutments for the stem by engaging enlarged flange 9. In use, the stem is relatively stationary, and the hammer 6 is reciprocated manually to bring the abutments 19 and 26 alternately against said flange.

When used for driving, a suitable element 13 is applied and, by placing said element in operative position, grasping the hammer by its non-slip portion 15, and moving the hammer, so grasped, to bring the abutment 26 into sharp percussive engagement with flange 9, a driving or pushing operation is accomplished. Similarly

but oppositely, by applying a pulling element to the tool and moving the hammer to bring the abutment 19 into sharp percussive engagement with flange 9, a lifting or pulling operation is performed. It is evident that the keying non-rotational engagement on the flat-sided flange 9 in the flat-sided passage 18 will result in a rotative movement of the stem and of an element applied thereto, upon a rotative movement of the hammer 6.

Having the hand partly resting on the hammer 6 and partly on the stem 8 can result in no harm in the present tool, since the shank extension 8 is smooth and without projectors which, in prior tools, often painfully pinched the portion of the hand resting on the stem.

It is to be understood that spline or key means may be employed instead of the flat faces 11 and 20. However, such flat faces are preferred, since they make assembling easier and provide a stronger tool. Both the flat faces and the spline or key means are called "keying means" in the hereunto appended claims.

While I have illustrated and described what I now regard as the preferred embodiment of my invention, the construction is, of course, subject to modifications without departing from the spirit and scope of my invention. I therefore, do not wish to restrict myself to the particular form of construction illustrated and described, but desire to avail myself of all modifications that may fall within the scope of the appended claims.

Having thus described my invention, what I claim and desire to secure by Letters Patent is:

1. A slide percussion tool comprising an elongated stem having a flat-sided flange intermediate its ends, a sleeve member having a flat-sided axial passage for axial movement therein of said flange, an integral abutment for said flange at one end of the sleeve member and defining one end of said flat-sided axial passage, and a collar carried by the end of the sleeve member opposite said abutment and having an end wall comprising an opposite abutment for said flange, said end wall of said sleeve member defining the opposite end of the flat-sided passage.

2. A slide percussion tool comprising an elongated stem having a flat-sided flange intermediate its ends, a sleeve member having a flat-sided axial passage for axial movement therein of said flange, an integral abutment for said flange at one end of the sleeve member and defining one end of said flat-sided axial passage, and a collar threadedly carried by the end of the sleeve member opposite said abutment and having a cylindrical axial passage forming an extension of the passage in the sleeve member and adapted to guide said stem, said collar having an end wall comprising an opposite abutment for said flange of the stem and defining the opposite end of the flat-sided axial passage.

3. In a percussion tool, an operating sleeve having opposed internal and spaced end abut-

ments and having an axial passage therethrough, said passage between the abutments having at least one flat longitudinal side terminating at each end at the abutments, and a stem extending through said passage and formed with an integral intermediate flange shaped to slidably fit the passage and the flat side thereof and movable between said abutments.

4. In a percussion tool, an operating sleeve having opposed internal and spaced end abutments and having an axial passage therethrough, said passage between the abutments having at least one flat longitudinal side terminating at each end at the abutments, one of said abutments being integrally formed on the sleeve and the other being removably connected thereto and a stem extending through said passage and formed with an integral intermediate flange shaped to slidably fit the passage and the flat side thereof and movable between said abutments.

5. A percussion tool comprising a hand-grasping element having a circular opening in one end and an aligned larger internally threaded opening in the other end, said element having a cylindrical passage larger than the circular opening to define an internal abutment shoulder adjacent one end of said element, said passage being smaller than the internally threaded opening, a collar threadedly engaged in the threaded opening and having a circular opening therein, said collar having an inner end wall defining an internal abutment shoulder opposite to the mentioned abutment shoulder, said cylindrical passage having at least one flat side that extends from abutment to abutment and is substantially tangent to the two circular openings, there being an outwardly directed shoulder at the end of said flat side that comprises a locating shoulder for said collar, and a stem extending freely axially through the hand-grasping element and having a flange intermediate its end, said flange having a flat-sided cylindrical form to accord with the form of the passage to hold the stem non-rotationally in the hand-grasping element during movement of said flange between abutments.
